UNITED STATES PATENT OFFICE.

JOHN BROUH, OF MANCHESTER, CONNECTICUT.

LINE-HOLDER.

SPECIFICATION forming part of Letters Patent No. 623,072, dated April 11, 1899.

Application filed October 1, 1898. Serial No. 692,428. (No model.)

To all whom it may concern:

Be it known that I, JOHN BROUH, a citizen of the United States, residing at Manchester, in the county of Hartford and State of Connecticut, have invented certain new and useful Improvements in Line-Holders; and I do hereby declare the following to be a full, clear, and exact description of the invention, such as will enable others skilled in the art to which

it appertains to make and use the same.

This invention relates to automatically-operating rein-holding devices for vehicles to prevent draft-animals from running away from a standing position during the absence of the driver or occupants of vehicles.

The invention primarily consists of a vertically-movable rein-holding toothed bar, an adjustable shaft carrying at one end a pinion meshing with said bar and operating the latter in one direction and on the opposite end a gear engaging an internal toothed disk on one of the wheels, said shaft having a spring surrounding it which is wound thereon by rotation in a forward direction and unwound by the backward movement of the vehicle, which reverses the movement of the shaft and pinion and raises the bar upwardly into a normal position, and a shifting lever for sliding said shaft and throwing the gear on the outer end thereof into or out of engagement with the said toothed disk.

The invention further consists of the details of construction and arrangement of the several parts, which will be more fully hereinafter described and claimed.

The object of the invention is to effectually check unusual movements of a horse or horses when left standing without requiring the employment of a common hitching-strap and obviating the delay incident to hitching and unhitching a horse or horses and insuring a safe detention of the draft-animals at all times when desired through the medium of devices carried directly by the vehicle and adapted to be adjusted when not in use to avoid interference with the free movement of the vehicle under ordinary conditions.

In the accompanying drawings, Figure 1 is a perspective view of a part of the body of a vehicle and running-gear, showing the improved device applied thereto and as operating to draw on the reins. Fig. 2 is a sectional

elevation of the arrangement of parts shown by Fig. 1 and illustrating them in normal position. Fig. 3 is a longitudinal section of the arrangement shown by Fig. 2, looking toward the wheel carrying the toothed operating-disk. Fig. 4 is a sectional elevation illustrating similar parts, including the toothed disk on the wheel and the gear engaging the same on the operating-shaft of the improved device. Fig. 5 is an enlarged sectional elevation of a part of the device to illustrate particularly the toothed rein-holding bar, the operating-shaft and pinion therefor, and means for adjusting and returning the several parts to a normal position.

Referring to the drawings, wherein similar numerals are utilized to indicate corresponding parts in the several views, the numeral 1 designates a vehicle-body, which may be of any form or adapted to any particular service and has in connection therewith, as in all such devices, a front axle 2, with opposite wheels 3. On the axle 2 is secured an axle-beam 4, between which and a body-bolster 5 a fifth-wheel or turning-circle 6 is located. Directly secured against the inside of the dashboard or front end 7 of the vehicle-body are a pair of flanged guides 8, in which a toothed rein-holding bar 9 is vertically mounted and provided at its upper end with a hook 10. In suitable bearings 11, 12, and 13, secured to the body of the bolster 5 at various points, a shaft 14 is mounted and runs parallel with the axle 2. This shaft 14 is movable in the bearings specified, and at a suitable point thereon collars 15 are fitted and spaced apart from each other, and between the same the lower apertured end 16 of a shifting lever 17 engages the shaft and is pivoted, preferably, to the body, as at 18, so as to be shifted either to the right or left in a plane parallel with the transverse extent of the dashboard. The shifting lever 17 is adapted to be engaged by a hook or keeper 19, attached at a suitable elevation on the inner surface of the dashboard or front end of the wagon-body and is intended to hold the shaft 14 inward, for a purpose which will be presently described.

On the inner end of the shaft 14 a pinion 20 is keyed and is of less thickness than the toothed rein-holding bar 9, with which it con-

tinually engages. Between the nearest collar 15 and the said pinion 20 a spring 21 is coiled about the shaft and has one end secured to said pinion and the opposite end connected to the said collar. On the outer end of the shaft 14 a gear 22 is fixed and is adapted to be thrown into and out of mesh with an internal toothed disk 23, carried by one of the wheels 3 and rotating with the latter. The collars 15 are preferably carried at the opposite ends of a sleeve, which is also fixed to the shaft 14 and engaged by the lower apertured end 16 of the shifting lever to avoid wear directly on the shaft, as will be obviously apparent.

The operation is as follows: When it is desired to leave a vehicle and bring the improved attachments into operation, the shifting lever 17 is thrown to the right and causes the gear 22 on the outer end of the shaft 14 to fall into mesh with the teeth of the disk 23. The reins are then attached to the hook 10 on the upper end of the toothed rein-holding bar 9. If the draft animal or animals start to move in a forward direction, the wheel 3, carrying the disk 23, is rotated, and also said disk, and the shaft 14 is revolved in the same direction. The revolution of the shaft 14 necessarily turns the pinion 20, which, meshing with the toothed rein-holding bar 9, causes the latter to move downwardly, as shown in Fig. 1, and exert a tension on the reins, which is increased as long as the draft animal or animals continue to advance. A pull of the reins on the animal or animals will necessarily check them and cause a backward movement. During the time that the shaft 14 has been revolving in a forward direction the spring 21 has been wound on the said shaft, and as soon as a backward movement ensues the said spring unwinds through its resiliency or tendency to return to its normal condition, and the revolution of the pinion 20 is reversed, thereby moving the bar 9 upwardly and slackening the reins. A continual advance movement by the draft animal or animals and the resultant operation of the device specified exerting a pull on the reins will cause a cessation of such movement or tendency of the animal or animals.

On returning to the vehicle the occupant or driver will shift the lever 17 toward the left until it engages the hook 19, and by this movement the shaft 14 is thrown to the right until the gear 22 is disengaged from the disk

23, and in this condition the running-gear of the vehicle is not in the least interfered with either when running straight or turning, and by having the shifting lever in engagement with the hook 19 accidental outward movement of the shaft 14, arising from vibration of the vehicle, will be avoided.

It is obviously apparent that changes in the proportions, dimensions, and details of construction might be resorted to without in the least departing from the nature or spirit of the invention.

Having thus described the invention, what is claimed as new is—

1. In a device of the character set forth, the combination of a vertically-movable toothed rein-holding bar, an adjustable shaft carrying a pinion on its inner end in engagement with said bar and a gear on the outer end of the same, a wheel having a toothed disk with which the gear on the outer end of the shaft is adapted to mesh, and a spring surrounding a portion of the shaft and having one end attached to one of the bearings of the latter and the opposite end to said pinion. 80

2. In a device of the character set forth, the combination of a vertically-movable toothed rein-holding bar, an adjustable shaft having a pinion on the inner portion thereof in continual mesh with the said bar and a gear on the outer end of the same, and a toothed disk with which the gear on the outer end of the shaft is adapted to mesh. 85

3. In a device of the character set forth, the combination of a vertically-movable toothed rein-holding bar, a shaft having a pinion on the inner portion thereof and engaging the said bar and a gear on the outer end of the same, a wheel having a toothed disk adapted to mesh with the said gear on the outer end of the shaft, a spring surrounding a portion of the shaft connected at one end to the pinion and at the other end to one of the bearings of the said shaft, and a shifting lever having its lower end engaging said shaft for the purpose of moving the latter inwardly or outwardly to throw the said gear out of or in mesh with the disk. 95 100

In testimony whereof I affix my signature in presence of two witnesses.

JOHN BROUGH.
